(57) CLAIM

The ornamental design for a canopy, as shown and described.

DESCRIPTION

FIG. 1 is a perspective view of a canopy showing my new design;

FIG. 2 is a front side view of the canopy shown in FIG. 1;
FIG. 3 is a right side view of the canopy shown in FIG. 1;
FIG. 4 is a top view of the canopy shown in FIG. 1;
FIG. 5 is a left side view of the canopy shown in FIG. 1;
FIG. 6 is a back side view of the canopy shown in FIG. 1; and,
FIG. 7 is a bottom view of the canopy shown in FIG. 1.
The broken lines in FIG. 7 represent portions of the article that form no part of the claim.
